T. J. W. BROWN.
MARKER FOR GOLF COURSES.
APPLICATION FILED APR. 1, 1915.

1,171,699.

Patented Feb. 15, 1916.

UNITED STATES PATENT OFFICE.

THOMAS J. W. BROWN, OF WASHINGTON, DISTRICT OF COLUMBIA.

MARKER FOR GOLF-COURSES.

1,171,699.

Specification of Letters Patent. Patented Feb. 15, 1916.

Application filed April 1, 1915. Serial No. 18,452.

To all whom it may concern:

Be it known that I, THOMAS J. W. BROWN, a citizen of the United States, residing at Washington, in the District of Columbia, have invented certain new and useful Improvements in Markers for Golf-Courses; and I do hereby declare the following to be a full, clear, and exact description of the invention, such as will enable others skilled in the art to which it appertains to make and use the same.

My invention relates to the game of golf, and particularly to markers for golf courses. As is well understood such markers usually consist of flags, or various shaped disks and targets having distinguishing marks, colors or numbers, mounted upon a suitable flag-stick or standard normally resting in an upright position within the holes of a golf course. In this position these markers indicate to players the position of distant holes, and it is also understood, by persons familiar with the game, that it is the duty of a caddie to remove the said flag-stick or standard as the ball approaches the hole during the putting operation, under penalty of losing the hole provided the ball fouls with said standard either before or after it has been removed. Ordinarily the said holes are each provided with a cylindrical metallic lining, having a within-contained funnel-shaped holder adapted to receive loosely the lowermost end of said flag-stick or standard to maintain it in a vertical position. Nevertheless, it frequently happens that in holding such standards caddies approach needlessly close to a particular golf hole, and carelessly tread down or break down the lip or edge thereof, and otherwise injure the putting green adjacent to the hole by trampling it into irregular and uneven form, particularly when the ground is damp. To overcome this difficulty, and to facilitate the instant removal of flag-sticks or standards from golf holes when required is one object of the present invention.

Another object of the invention is to provide means whereby the flag section of a marker for golf courses is by gravity always maintained in a vertical position.

Another object is the production of an exceedingly simple, inexpensive and durable marker for golf courses, comprising a flag section and a handle section pivotally connected, the latter adapted to enter and be held upright at times by the central tubular

support common to golf holes proper, and said flag section being prevented by a terminal bulbous counterweight from entering said central tubular support.

With these and other objects and advantages in view the invention will now be particularly described and then set forth by the appended claims.

In the accompanying drawings which form part of this application for Letters Patent, and whereon corresponding numerals indicate like parts in the several views: Figure 1 is a side elevation of the invention comprising a flag section and a handle section pivotally connected at a point above the center of gravity of said flag section, a counterweight upon the lower end of the latter, and a depressed hole-lining or rim shown in central section within which said handle section is supported in a vertical position for use as a standing marker. Fig. 2 is also a side elevation of the invention with the hole-lining shown in section, but here the flag section is supported by the handle section as during play upon the putting green. Fig. 3 is a fragmentary detail view in perspective showing the form of pivotal connection employed in connecting the flag section and the handle section of a marker, and Fig. 4 is also a fragmentary detail view partly in plan and partly in section showing more especially the universal connection employed between the flag section and handle section of the invention.

Reference being had to the drawings and numerals thereon, 1 indicates a flag section or support having at its upper end a flag or target 2 of any approved form, and permanently secured to its opposite or lowermost end a bulbous counterweight 3 of relatively enlarged diameter. The numeral 4 indicates a handle section of the structure, which, as shown by Figs. 1 and 2, is pivotally connected to said flag section at a point above the center of gravity thereof. By preference rod or round merchant iron is the material of which said flag and handle sections 1 and 4 are made, because of the simplicity and cheapness of construction, and durability, although various other materials may be satisfactorily employed, as for example, bamboo. In any event, however, it is desirable, although not essential, to connect the said sections by a universal joint in order that the flag section 1 may be free to turn in all directions. In the

structure shown there is employed a perforated angle-plate 5 loosely and pivotally connected to the end of handle section 4 by a headed pintle 6 projecting from the latter as best shown by Fig. 4; while, as shown by the same figure, there is a pivot 7 located at right angles to the pintle 6, rigidly connected to the other angle of said plate 5, and passing transversely and loosely through the flag section 1.

The numeral 8 indicates an ordinary form of golf-hole-rim or lining, having the usual within contained central funnel shaped and tubular support 9 for a flag-stick or standard, and in practice this is depressed flush with or a trifle below the surface of the putting green.

The foregoing being a description of my invention in its preferred form of construction it should be understood that I am not restricted to any particular pivotal means for the connection of said flag and handle sections, or to any particular materials, sizes, shapes or relative proportion of parts employed. In like manner various changes and modified forms of construction may be made and substituted for those hereinbefore shown and described without materially departing from the spirit of the invention as claimed.

In practical operation the free end of handle section 4 is placed in the tubular supports 9 and is thus maintained in vertical position for marking distant holes upon the golf course. Upon reaching a putting green, however, the marker is by a caddie removed from its said standing position, the flag section 1 being then similarly introduced within the hole lining 8 by means of the handle section 4 as shown by Fig. 2 of the drawings, ready for instant removal by agency of said handle section an instant before the ball enters the hole. Obviously this operation is greatly facilitated by the fact that said flag section 1 is pivotally connected to said handle section 4 at a point above the center of gravity of the flag section, and especially by the fact that such is a universal

connection thus making it possible to introduce the end of the flag section into the 50 hole lining 8, or withdraw it therefrom, in a true perpendicular position regardless of the position of the handle section 4 either angularly or rotatably. It will also be observed that the bulbous counterweight 3 being of greater diameter than the tubular support 9 bridges the latter, and prevents the possibility of the flag section 1 entering said tubular support. As a consequence it is impossible for the flag section to become tube-bound as frequently happens with ordinary flag sticks oftentimes causing a player to lose the hole.

Having thus described my invention what I now claim and desire to secure by Letters Patent is:

1. A marker for golf courses comprising in combination a flag section and a handle section having a pivotal connection at the end thereof universally secured at a point above the center of gravity of the said flag section.

2. A marker for golf courses comprising in combination a flag section and a handle section connected by a universal joint at a point above the center of gravity of the said flag section.

3. A marker for golf courses comprising in combination a counterweighted flag section and a handle section having a pivotal connection at the extreme end thereof universally secured at a point above the center of gravity of the said flag section.

4. A marker for golf courses comprising in combination a flag section having an enlarged bulbous counterweight at its lower end, and a handle section connected by a universal joint to said flag section at a point above the center of gravity of the latter.

In testimony whereof I affix my signature, in presence of two subscribing witnesses.

THOMAS J. W. BROWN.

Witnesses:

THOMAS DURANT,
WM. E. DYRE.
